Attorney.

UNITED STATES PATENT OFFICE

WALTER C. BROUGHTON, OF KANSAS CITY, MISSOURI

BURIAL VAULT

Application filed August 27, 1928. Serial No. 302,298.

Heretofore it has been customary to undertake the protecting of burial caskets from water and decay while in the grave by first placing them in a concrete case, or lowering 5 a metal jacket over the casket before the loose earth is thrown back into the grave. As the concrete case is more or less porous, moisture will in the course of time soak through and cause the enclosed wood burial casket to decay, while if the metal jacket is employed it will eventually be crushed or bent out of shape by the weight of the earth thereon and thereby fail to properly seal the enclosed casket from the entrance of water.

15 In carrying out my invention I overcome the foregoing objections by inclosing the burial casket in a water-tight metallic jacket which in turn is enclosed in a concrete case protected by a metallic cover. The jacket 20 is spaced from the casket and the concrete case is spaced from said jacket and the outer metal cover, thereby providing three air spaces for the preservation of the wood burial casket.

25 The metallic jacket and the outer metallic cover being air and water-tight prevent those elements from attacking and destroying the enclosed burial casket, while the concrete case 4 is so formed as to sustain the top and sides 30 of the outer metallic cover so that the latter can carry the earth thereon without becoming bent out of shape.

In order that the invention may be fully understood, reference will now be had to the 35 accompanying drawings, in which:

Fig. 1 is a longitudinal section of the burial vault.

Fig. 2 is a cross section of the burial vault on line 2—2 of Fig. 1.

40 Fig. 3 is a perspective view showing several parts of the concrete case detached from each other.

Fig. 4 is a fragmentary plan view of portions of the concrete case and the inner metal 45 jacket.

Referring in detail to the different parts, A designates the burial casket which is usually made of wood and forms no part of the present invention. 2 designates an inner metal jacket which is closed at the top, sides,

and ends but is open at the bottom so that it may be lowered over the casket A.

4 designates the case which consists of concrete or like material which will last indefinitely when buried in the grave. 55 Said case 4 is preferably made in knock-down form to facilitate the manufacture thereof and so that the several parts can be readily transported and lowered into the grave. The case 4 comprises a bottom wall 60 6, a pair of side walls 8, a pair of end walls 10, and a lid 12. All of said walls are detachable from each other for the purposes above set forth and are assembled in the grave preparatory to receiving the casket A and 65 the inner metal jacket 2.

The bottom wall 6 has a large recess 14 extending over almost the entire area of the under side thereof for a purpose which will hereinafter appear. The upper side of the 70 bottom wall 6 is reinforced by a plurality of ribs 16 which also constitute a support for the casket A. An offset 18 extends entirely around the margins of the bottom wall 6 for the reception of the lower edges of the 75 side walls 8 and the end walls 10, which are reinforced at their outer sides with transverse ribs 20 and 22, respectively.

The lid 12, like the bottom wall 6, has a marginal offset 24 extending entirely around 80 its under side for the reception of the upper margins of the side walls 8 and the end walls 10. The upper surface of the lid 12 inclines in opposite directions from a central ridge 28 and is reinforced by a plurality of transverse ribs 30. The ends of the side walls 8 have vertical offsets 31 for receiving the ends of the end walls 10.

32 designates an outer metal cover which is entirely enclosed, except at its under side 85 which is left open so that it may be lowered over the case 4.

In practice the bottom wall 6 of the case 4 is first lowered into the grave, the bottom of which latter is made relatively smooth so 90 that air will be entrapped in the recess 14 and thereby prevent moisture from seeping through said bottom wall 6 and reaching the casket A. The side walls 8 and the end walls 10 are then lowered one by one and placed 100

in position by resting their lower margins in the offset 18 of the bottom wall 6. The side and end walls 8 and 10, respectively, are then secured together with pliable means such as 5 copper or other noncorrosive wires 11, some of which are embedded at one end in the walls 8 while the others have one end embedded in the walls 10. When the case 4 has thus been set up for use the casket A is lowered upon the ribs 16, after which the inner jacket 2 is lowered to cover the casket A and rest upon the bottom wall 6. The jacket 2 is firmly held upon the bottom wall 6 with the wires 11, the free ends of which are passed 10 through eyes 18 on the jacket 2. The lid 12 is then lowered into position upon the upper margins of the side and end walls 8 and 10, respectively, and coacts with the bottom wall 6 and the wires 11 in firmly holding 15 the case 4 in assembled position. The outer metal cover 32 is next lowered over the case 4 and its lower margins are slightly embedded in the bottom of the grave to form an air and water-tight joint. The ribs 20, 22 and 30 hold the outer cover 32 in spaced 20 relation to the concrete case 4 and with the recess 14 leave a dry air space 34 almost entirely around the case 4 so that moisture cannot reach the latter. The ribs 20, 22 and 30 25 also support and reinforce the outer metal cover 32 and thus prevent it from becoming bent out of shape or crushed in by the weight of the dirt resting thereon. The inner metal jacket 2, covering the casket A is spaced from 30 the latter to leave an air space 35, and the case 4 is spaced from said jacket 2 and the outer cover 32 to leave air spaces 36 and 34, respectively.

From the foregoing description it is apparent 35 that I have provided a triple air space for preserving and keeping the casket A dry and sealing it against the entrance of moisture, and while I have shown and described one form of the invention I reserve all rights 40 to such other forms and modifications thereof as properly fall within the spirit and scope of the invention as claimed.

Having thus described my invention, what I claim and desire to secure by Letters Patent, is:

In combination, a case having side, end and bottom walls, ribs on the upper surface of the bottom wall for supporting a burial casket, said ribs being shorter than the width 55 of the bottom wall, a metal jacket adapted to extend over the top, side and end walls of said casket and rest at its lower margins upon the bottom wall of the case, the opposite sides of said jacket abutting the ends of said ribs to hold the jacket in spaced relation to the inner surface of the case, and a lid for 60 said case.

In testimony whereof I affix my signature.
WALTER C. BROUGHTON.
